UNITED STATES PATENT OFFICE.

GEORGE J. C. LAMMERS AND ALFRED F. R. LAMMERS, OF AKRON, IOWA.

MULTIPLE-SOCKET WRENCH.

Application filed September 12, 1925. Serial No. 55,887.

This invention relates to socket wrenches and more particularly to types embodying a series of nut receiving sockets in a single tool.

5 One of the objects is to provide a nested series of sockets combined in a unitary handle, each individual socket being slidable into positions for service without interference of the remaining sockets.

10 A further feature is in the provision of a multiple socket wrench in which all of the sockets are arranged about a common axis, movable into operative position independently, and there securely held.

15 Another aim is to provide a simple and compact wrench and combine an effective operative means therewith giving ample leverage to any socket which may be desired.

These and other objects which will become 20 manifest, are secured by the novel construction and combination of parts hereinafter described and shown in the accompanying drawing, forming a material part of this disclosure, and in which:—

25 Figure 1 is a longitudinal sectional view taken through the center of a wrench made in accordance with the invention.

Figure 2 is a side elevational view of the same.

30 Figure 3 is a transverse sectional view taken on line 3—3 of Figure 1.

Figure 4 is a fragmentary sectional view, similar to Figure 1, but showing one of the intermediate sockets as operatively engaged.

35 Figure 5 is a further fragmentary sectional view showing the innermost sockets as extended.

Referring more in detail to the drawing, the numeral 10 designates a generally cylindrical handle having a central longitudinal slot 11, in which is disposed a lever 12, pivoted on a transverse pin 13, this lever being swung outward at one side when used in turning the wrench, as shown in the broken lines in Figure 1.

40 The outer end of the handle is solid and the inner end 14 is reduced to form a hexagon, over which is disposed a hexagonal steel tube 15, rigidly held by a pin 16.

45 The tube 15, as will be seen, constitutes the outer, longest and largest of the several sockets, which are closely nested therewithin, as shown at 17, 18, 19 and 20, thus giving five ranges of sizes which may be operated by the wrench.

All these several hexagonal tubes, except the outermost, are freely slidable one within another and are movable by pins 17^a, 18^a, 19^a and 20^a, set in the respective tubes and extending uniformly outward through slots 60 15^b, 17^b, 18^b and 19^b in their adjacent sides, these slots being formed longitudinally and in register.

Similar but narrower slots 15^c, 17^c, 18^c and 19^c are formed in the opposite side walls of 65 the hexagonal tubes through which pass pins 17^d, 18^d, 19^d and 20^d fixed in their respective tubes to extend uniformly outward.

A spring detent 21 is fixed on one of the 70 walls of the outer tube 15, bent lengthwise to present a portion 22, provided with a series of angular notches 23 on its edge adapted to engage any of the pins 17^d, 18^d, 19^d and 20^d, this detent having an extending lug 24 by which it may be retracted when shifting the sockets.

It is to be noted that the shape of the teeth 75 23 permit extension of any desired socket and prevent its retraction until the detent has been manipulated.

It will also be seen that the several sockets are progressively shorter toward the center of the wrench and the innermost socket is provided near its operative end with a solid block 25 acting as a re-enforcement in a manner similar to the interaction of the several tubes.

80 From the foregoing it will be seen that a simple and effective wrench has been disclosed in the preferred form of its embodiment, but changes may be made therein without departing from the spirit and scope of the invention as claimed.

Having thus described our invention, and set forth its operativeness and use, what we 85 claim as new and desire to secure by Letters Patent, is:—

1. A multiple socket wrench comprising a series of nested hexagonal sockets, a slotted handle in the outer socket, a lever pivoted in 100 said handle to be extended at an angle thereto, the outer socket being fixed and the inner sockets slidable therein, means for projecting a selected socket into position for use, pins in each socket extending outwardly beyond the outermost socket, and a spring lever having teeth to engage said pins selectively.

105 2. A multiple socket wrench comprising a series of nested sockets, a unitary slotted handle in the outer socket, means to project 110

any selected socket, and toothed resilient means to maintain the selected socket when projected.

3. A multiple socket wrench comprising a series of nested sockets, said sockets containing slots in their opposite sides, pins fixed in each socket to extend through the slots on one side of the adjacent sockets, said pins acting as handles to move selected

10
sockets outward, other pins in the opposite sides of the sockets extending through the adjacent slots, and a spring detent engageable with any of the last named pins.

In witness whereof we have signed our names to this specification.

GEORGE J. C. LAMMERS.
ALFRED F. R. LAMMERS.
